(57) **CLAIM**

The ornamental design for an insulating container with cover for a beverage can, as shown and described.

DESCRIPTION

FIG. 1 is a front perspective view of an insulating container with cover for a beverage can showing my new design;
FIG. 2 is a bottom perspective view thereof;
FIG. 3 is a front perspective view of the design in a second configuration with a closure in an open position;
FIG. 4 is an exploded view thereof;
FIG. 5 is bottom perspective view of the cover of the design;
FIG. 6 is a front view of FIG. 1;
FIG. 7 is a bottom view thereof;
FIG. 8 is a top view thereof;
FIG. 9 is a top view of FIG. 3; and,
FIG. 10 is a bottom view of FIG. 5.
All broken lines in the drawings are for illustrative purposes only and form no part of the claimed design.
